FLUE GAS DISTRIBUTION IN HEATING FURNACES

William H. Dailey, Jr., Toledo, Ohio, assignor, by mesne assignments, to Midland-Ross Corporation, Cleveland, Ohio, a corporation of Ohio

Application October 1, 1956, Serial No. 613,239

7 Claims. (Cl. 263—40)

The present invention relates to metallurgical furnaces for heating ingots, billets, blooms, slabs and the like preparatory to plastic deformation by rolling, forging, etc. and particularly to an improved method and apparatus for controlling combustion gas, or flue-gas, distribution in slab heaters.

In the control of flue gas distribution it is desirable that the flow of the flue gases through the heating chamber be maintained in such a manner as to prevent melting, generally referred to as "washing" or "burning," of the initially formed scale at the slab edges and end surfaces.

In the present practice of heating slabs it is customary to pass the work through the heating chamber upon elevated skid rail supports. When the furnace is filled with slabs, the row of slabs supported on the skids separates the heating chamber into top and bottom sections. The flue gases from the furnace are discharged into an exhaust or flue duct ordinarily provided at the charge end of the furnace. Generally the flue connects to the furnace from below the stock line, and passes flue gas through a recuperator, if desired, and thence to an exhaust stack. In some cases the flue may connect to the furnace above the stock line, but for purposes of illustration the former type of flue connection is referred to herein.

With a bottom-connected flue, the gases from the bottom heating section discharge directly into the flue while those gases from the top heating section must pass through side downcomers and into the flue. The side downcomers and passages have an inherently high resistance to flue gas flow, especially at the stock line, which forces the flue gases in the top heating section to flow downward around the slabs before the gases have travelled the entire length of the chamber. As the flue gases flow downward into the bottom heating chamber section they overheat the slab edges, causing the "washing" above described.

The principal object of this invention is the provision of a method and apparatus which overcomes the tendency of the flue gases to flow from one side of the stock line to the other before reaching the flue area, and thus avoids the "washing" of slabs.

An advantage of the present invention is the provision of structure in the heating chamber which forms orifices for effecting the proportioning of the pressure drop of the flue gases from the heating chamber section through the exhaust manifold by adjusting the relative rates of flow of said flue gases.

A further advantage is the provision of a variable restrictor to regulate the volume of gases flowing from one heating chamber section to correspond with a predetermined volume of gases flowing through the other heating chamber section.

For a consideration of what I believe to be novel and my invention, attention is directed to the following specification, the drawing and the concluding claims.

In the drawings:

Fig. 1 is a schematic representation of a slab heater furnace embodying the present invention with gas flow

2

restrictors at the charge end, the operating cylinder of one restrictor being shown responsive to a pressure regulating control device;

Fig. 2 is a fragmentary schematic view taken on line 5 2—2 of Fig. 1, indicating the position of a downcomer flue passage;

Fig. 3 is a view similar to Fig. 1 with the operating cylinder of the bottom restrictor being shown responsive to the fuel flow to the burners;

Fig. 4 is a schematic representation of a slab heater furnace having a restrictor of preadjusted size;

Fig. 5 shows an alternate, manually adjustable restrictor.

Referring to Fig. 1, the numeral 10 designates the heating chamber of the furnace and the numeral 16 designates the "soaking" chamber. The furnace is provided with water-cooled pipes or skid rails 11 on which the billets 12 or other work to be heated are supported within the furnace. The skid rails are supported for 20 part of their length by transverse pipe supports or beams 13. When the furnace is filled with billets 12, the row of billets supported on the skid rails 11 separates the heating chamber into an upper section 14 and lower section 15.

Heat is supplied to the heating chamber sections 14, 15 and the soaking chamber 16 through burners 17, 18 and 19, respectively, to which fuel and air are supplied. Temperature control means 60, responsive to temperature measuring device 61, any of several well known 30 types, may be employed to adjust the rate of supplying combustion gases, fuel and/or air, to any or all of the burners 17, 18 and 19 through valve 62. (Such temperature measuring and responsive means, for the purpose of simplicity, is only shown in Fig. 3 in cooperation with burner 17.) The products of combustion from burners 17 and 19 travel over the billets towards the charge end of the furnace through an orifice 20 defined by the billets 12 and a depending baffle 21 to the side wing sections or downcomers 22. The products of combustion from 35 the burner 18 travel beneath the billets through orifice 25 defined by the billets 12 and a lower baffle 26. While an upper baffle or arch 21 is illustrated in Figs. 1 and 3, the clearance between the edges of the billets and the furnace wall in the downcomer section may be designed 40 to provide the orifice 20 at the stock line, between the slab edges and the downcomers 22 at the point of minimum cross-sectional area, as is illustrated in Fig. 4.

The flue gases from above and below the work being heated discharge into a plenum chamber 52 whose cross-sectional area is at least as large as the sum of the effective areas of orifices 20 and 25, thus providing a common downstream pressure for said orifices.

The present invention is primarily concerned with the 55 exhaust flue gas orifices 20 and 25 and the control relating thereto to regulate distribution of combustion gases within the heating chamber section. The remaining construction and operation of the furnace are well known and not illustrated.

The baffle 21, or side wing sections or downcomers 22 especially at the minimum cross-sectional area at the stock line, have an inherent relatively high resistance to the flow of the exhaust gases therethrough, thereby building up a pressure in the upper heating chamber section 14. This pressure tends to force the gases to flow from 60 the upper section 14 past the billet edges to the lower section 15 of the heating chamber 10 thereby overheating the edges of the billets.

In Fig. 1, the pressures in the upper section 14 and the lower section 15 are measured by means of pressure 65 taps 31 and 32 respectively. The pressure signals are transmitted to opposite sides of a diaphragm 30 of a hydraulically operated regulator 29, which may be of

the type commercially known as "Askania." The diaphragm is operatively connected to a pivotable jet pipe 33. With the pipe 33 in a mid-position, equal pressures exist in each receiving orifice. The orifices are directly connected to opposite sides of piston 34 within power cylinder 28. A difference in pressures between the upper and lower furnace sections beyond the static pressure head will cause the jet pipe 33 to deflect and transmit more hydraulic fluid to one side of the piston 34 than the other. This causes the piston 34 to move at a rate proportional to the difference in pressures between the upper and lower sections. The movement of the piston 34 adjusts the position of the lower baffle 26 so that the pressures in the upper and lower sections will be in equilibrium.

It is the contemplation of the invention to establish and maintain a pressure differential between the upper chamber section 14 and the exhaust manifold 23 equal to the sum of the pressure differential between the lower chamber section 15 and the exhaust manifold 23 plus the static pressure head between the upper 14 and lower 15 chamber sections. This relationship may be expressed mathematically by the formula:

$$P_1 - P_2 = (P_1 - P_3) + P_4$$

where

P_1 = Pressure in the exhaust manifold

P_2 = Pressure in the upper heating chamber

P_3 = Pressure in the lower heating chamber

P_4 = The static pressure head between the upper and lower heating chambers at the existing temperature.

The maintenance of such a pressure differential enables the flue gases in the upper section 14 to flow the entire length of the chamber 10 before passing downward to the exhaust manifold 23 through the down-comers 22 and thereby prevents overheating of the slab edges.

The embodiment in Fig. 1 discloses a method of obtaining the pressure differential desideratum in response to a direct measurement of the difference in pressures in the upper and lower heating chambers. This desideratum may also be made responsive to factors which influence the pressures.

The volume of gases flowing in a section is a factor which influences the pressure in that section and is a reflection of the fuel flow to the burner of that section. As an alternative shown in Fig. 3, the adjusting cylinder may be made to respond to a ratio device 43 which measures the ratio of fuel flow to the burners whose products should flow through the upper heating section with fuel flow to the burners whose products should flow through the lower heating section. The flow through burners 17 and 19, as measured by orifice meters 45 and 46, respectively, initiate signals T and S respectively, to totalizer 44 which in turn initiates a signal A to the ratio transmitter 43. The flow through burner 18 as measured by orifice meter 47 also initiates a signal B to the transmitter 43. The transmitter proportions the signals A and B into a new signal N which may be expressed

$$N = \frac{A}{B} = \frac{T+S}{B}$$

An increase in the fuel flow to burners 17 and 19 increases the pressure in the top heating section and the value of A. Assuming no increase in fuel flow to burner 18 and hence no increase in the pressure in the lower heating zone, the increase in signal A will produce an increase in signal N which is transmitted to piston positioner 50 which sends an impulse to cylinder 28 to move the piston 34 upward to raise the baffle 26, thus increasing the pressure in the bottom heating section to correspond to that of the top heating section.

Conversely, if an excessive firing rate occurs in burner 18, the piston positioner 50 will move the piston 34 down-

ward to lower the baffle 26 and decrease the lower heating section pressure.

As another alternative, shown in Fig. 4, the pressure differential desideratum may be obtained by building the height of the lower baffle, comprising pier 53 and bricks 27, to a precalculated level and then controlling the firing rate of the burner 18 so that the ratio of the mass of gases emitted from burners 17 and 19 flowing through upper orifice 20 to the mass of gases emitted from burner 18 and flowing through lower orifice 25 is in proportion to ratio of the area of the upper orifice 20 to the area of the lower orifice 25.

Pressure signals are transmitted from pressure taps 37, 38, and transmitted to opposite sides of a piston 40 which actuates damper 41 in the air supply line 42 to burner 18. The fuel is supplied proportionately by means well known but not shown.

When the pressure in upper heating chamber section 14 exceeds the pressure in lower heating chamber section 15 the impulses to piston will increase the firing rate to the lower heating chamber section 14 and concomitantly the pressure.

If the cross-sectional area of the downcomer 22 is small as compared with the cross-sectional area of the upper heating section 14 and the exhaust manifold 23 so that the downcomer 22 has the effect of an orifice, the upper baffle 21 may be eliminated as in Fig. 4.

As an alternate to the preadjusted lower baffle of Fig. 4, an externally manually (or automatically) adjustable damper 55 may be provided as shown in Fig. 5, the adjustment being effected by rotation of the shaft 54 from outside the furnace.

Since the volume of gases flowing in a section influences the pressure and is a reflection of the fuel flow to the burner of that section, the pressure may be regulated by adjusting the rate of supplying combustion gases to the section. This adjustment may be achieved by controlling the volume of fuel and air, that make up the combustion gases, to the burner. The pressure differential desideratum may be achieved by providing a baffle of predetermined height and then controlling the firing rate of burner 18 so that the ratio of the masses of gases emitted from burner 18 to the masses of gases emitted from burner 19 are in proportion to the ratio of the area of the lower orifice 25 to the area of the upper orifice 20.

It will be readily apparent to those skilled in the art that several combinations in the light of the disclosed means and methods described above can be made without departing from the scope of the invention.

While it is preferred to maintain the desired balanced pressure condition above discussed by automatic controls, thus effectively reducing or preventing by-passing of hot gases around the edges of the slabs before the gases enter the side downcomer area where the low gas velocity combined with relatively cold incoming slabs serves to avoid "washing," substantial advantage may be taken of the flue and damper design disclosed by adjusting the damper to provide a ratio of effective orifice areas suitable to prevent "washing" at the normal maximum firing rate. Thus as the firing rates of various burners drop off, the temperature conditions and flue gas velocities become less severe, and likelihood of "washing" due to gases passing around the ends of slabs from one heating chamber section to the other is substantially reduced.

It thus becomes apparent that the flue and damper design which provides restricted gas flow orifices discharging into a plenum area leading to the flue and stack system makes possible control of gas flow in a manner to prevent by-pass of flue gases from one heating section to the other, and thus makes possible faster heating rates, higher heating chamber temperatures and greater production rates without danger of overheating and "washing" of the slabs being heated.

The foregoing is an extensive disclosure of the principles involved in the present invention which will enable persons skilled in the art to take advantage of this invention in similar or equivalent forms.

I claim:

1. In a continuous furnace having a heating chamber through which hot combustion gases flow to an exhaust manifold, and containing elevated work support means which when work is placed thereupon divides said chamber into upper and lower sections, the combination comprising: first and second burner means for supplying combustion gases to one of said upper and lower sections; third burner means for supplying combustion gases to the other of said upper and lower sections; temperature responsive means for independently controlling the rates of supplying combustion gases from two of said burner means; and control means for controlling the rate of supplying combustion gases from the third of said burner means to maintain a substantially constant pressure difference between said upper and lower sections substantially equal to the static head therebetween.

2. In a continuous heating furnace having a soaking chamber and a heating chamber through which hot combustion gases flow to an exhaust manifold, and containing elevated work support means which when work is placed thereupon divides said heating chamber into upper and lower sections, and separate burner means for each of said upper and lower sections and the soaking chamber, the combination comprising: metering means for measuring the fuel flow through each of said burner means; means for transmitting an impulse representing the sum of the flow through the upper heating section burner means plus the flow through the soaking chamber burner means; means for transmitting an impulse representing the flow through the lower chamber burner means; ratio transmitting means, in operative engagement with the preceding two transmitting means, for transmitting a signal representing the ratio of the sum of the fuel flows through said upper section burner means and the soaking chamber burner means with the fuel flow through the lower chamber burner means; wall means for regulating the passage of gases from said upper section to the exhaust manifold; an adjustable baffle for regulating the passage of gases from said lower section to the exhaust manifold; adjusting mechanism for adjusting said adjustable baffle; and mechanism operatively associated with said adjusting mechanism for actuating the same in response to the signal from the ratio transmitting means.

3. In a heating furnace, in combination: a heating chamber having elevated work support means and through which hot combustion gases flow, the work when placed upon said support means dividing said chamber into upper and lower sections; a flue for discharging combustion gases from said chamber; an exhaust chamber discharging into said flue, first wall means forming with the work on said support means a first vertically restricted passage from one of said upper and lower sections into said exhaust chamber; and second wall means, in substantially vertical alignment with said first restriction, forming with the work on said support a second vertically restricted passage from the other of said upper and lower sections; the horizontal cross-sectional area of said exhaust chamber being greater than the sum of the effective vertical cross-sectional areas of said first and second restricted passages.

4. The combination according to claim 3 wherein said

first wall means comprises an adjustable damper for varying the effective vertical cross-sectional area of the first restricted passage.

5. In a continuous furnace having a heating chamber 5 through which hot combustion gases flow to an exhaust manifold, and containing elevated work support means which when work is placed thereon divides said chamber into upper and lower sections, the combination comprising: upper burner means for supplying hot combustion gases to said upper section; lower burner means for supplying combustion gases to said lower section; a first wall portion forming with work on said support means a first restricted flow passage from said upper section to said manifold; a second wall portion forming with work on said support means a restricted flow passage from said lower section to said manifold; and control means comprising temperature responsive means operatively connected to adjust the rate of supplying combustion gases from one of said upper and lower burner means, and means for adjusting the rate of supplying combustion gases from the other of said upper and lower burner means to maintain a pressure differential between said upper and lower sections substantially constant and equal to the static head pressure therebetween, whereby to substantially prevent passage of gases from one to the other of said sections and thereby avoid overheating the exposed ends of the work being heated.
6. The combination according to claim 5 wherein said means for adjusting the rate of supplying combustion gases from the other of said upper and lower burner means is responsive to the rate of supplying combustion gases to said one of said upper and lower burner means.
7. In a continuous furnace having a heating chamber 35 through which hot combustion gases flow to an exhaust manifold, and containing elevated work support means which when work is placed thereon divides said chamber into upper and lower sections, the combination comprising: upper burner means for supplying hot combustion gases to said upper section; lower burner means for supplying combustion gases to said lower section; a first wall portion forming with work on said support means a first restricted flow passage from said upper section to said manifold; a second wall portion forming with work on said support means a second restricted flow passage from said lower section to said manifold; and control means comprising damper means cooperating with one of said first and second wall portions, and means responsive to the rates of supplying combustion gases to each of said upper and lower sections and operatively connected to adjust the position of said damper means to maintain a pressure differential between the upper and lower sections substantially constant and equal to the static head pressure therebetween whereby to substantially prevent passage of gases from one to the other of said sections and thereby avoid overheating the exposed ends of the work being heated.
